RADIO RECEIVING SET

Stuart W. Seeley and Garrard Mountjoy, Jackson, Mich., assignors, by mesne assignments, to Radio Corporation of America, New York, N. Y., a corporation of Delaware

Application January 29, 1932, Serial No. 589,596

8 Claims. (Cl. 250—20)

This invention relates to radio receiving sets and is particularly useful in superheterodyne receiving sets with either audible or superaudible intermediate frequency.

5 In superheterodyne receiving sets the oscillator combines with the signal to produce a superaudible intermediate frequency. There are two signals that will combine with the oscillator frequency to produce the same beat or intermediate frequency. If k is the intermediate frequency and F_0 the oscillator frequency then these two frequencies are F_0+k and F_0-k . Therefore two stations transmitting at two frequencies will interfere with each other to an appreciable extent even though there is a preceding circuit tuned to the desired one of these frequencies.

10 The complementary or undesired signal is usually called the image frequency.

An object of the invention is to balance out the 15 effect of such frequency.

Other objects will appear in the following description, reference being had to the drawing in which:

20 Fig. 1 is a circuit diagram illustrating the principles of the invention.

Fig. 2 is the circuit of a modification.

In the drawing the antenna 1 is coupled through primary 2 to secondary 3, tuned by condenser 4 to the desired signal. This tuned circuit is designated A. The tuned circuit A is coupled to coil 5 in the grid circuit of the radio frequency amplifier 15. We have shown by way of example one such amplifier only, but more may be used if desired. The condenser 6 tunes this grid circuit coil to the desired signal frequency. This tuned circuit is designated B. Ordinarily the constants of these two tuned circuits would be identical and they will be assumed to have this relation in explaining our invention. The oscillator is indicated at 7 and the first detector is designated by 8. The intermediate frequency after detection at 8 may be amplified by amplifier 9, detected at 10, amplified at audio frequency at 11 and reproduced in the phones 12 or equivalent device. Since our invention relates to the balancing out of the image frequency we have not shown the details of the circuits after the radio frequency amplifier. These circuits may be standard and they will be understood by those skilled in the art. The source of grid and plate voltages has also been omitted to simplify the disclosure. We balance out the image frequency by introducing a very small capacity 13 between the antenna 1 and the radio frequency amplifier

grid. We may introduce this elsewhere, for example, directly into the grid circuit of the first detector, but it is preferable to introduce it into the grid circuit of the radio frequency amplifier and we have shown the condenser 13 as connected to the grid 14 of such amplifier.

To show how the condenser brings about the elimination of the image frequencies at substantially all the frequencies used in the present broadcast range it will be necessary to make a mathematical analysis as follows:

Let the following be assumed:

E_a =the voltage across primary 2 of the image frequency to be eliminated

15 L_1 =the inductance of primary 2

L_2 =the inductance of the secondaries 3 and 5

M_1 =the mutual inductance between 2 and 3

M_2 =the mutual inductance between 3 and 5

C_1 =the capacity of condensers 4 and 6

C_2 =the capacity of condenser 13

20 E_1 =the voltage of the image signal that reaches the grid 14 through the transformers

E_2 =the voltage of the image signal that reaches the grid 14 through the capacity 13

25 $W_s=2\pi$ times the desired signal frequency

$W=2\pi$ times the image frequency

30 I =current in coil 2

I_1 =current in circuit A

I_2 =current in circuit B

Then $W=W_s+K$ where K is a constant having 30 the value 4π times the intermediate frequency.

There are two paths through which the image frequency may reach the grid 14 of the amplifier tube. One is through the transformers 2, 3 and 35 3, 5. The other is through the small condenser 13.

Since the circuit A is out of tune with the image frequency and the coupling is loose the secondary of the transformer does not materially affect the impedance of the primary. Therefore 40 the current I in coil 2 is:

$$\frac{E_a}{jWL_1}$$

45 The voltage induced in coil 3 by E_a is equal to the mutual inductance M_1 multiplied by the current I in coil 2. Its value is therefore jWM_1I . Substituting the value of I, the voltage becomes

$$\frac{jWM_1E_a}{jWL_1}$$

50 or

$$\frac{E_aM_1}{L_1}$$

55

The current of I_1 in the circuit A is the voltage divided by the impedance Z of the tuned loop.

$$Z = jWL_2 - \frac{j}{WC_1}$$

5 now

$$C_1 = \frac{1}{W_s^2 L_2}$$

and since $W_s = W - K$

$$C_1 = \frac{1}{(W - K)^2 L_2}$$

Substituting this value of C_1 ,

$$Z = jKL_2 - \frac{(2W - K)}{W}$$

15 Therefore

$$I_1 = \frac{E_a M_1}{jKL_1 L_2} \times \frac{W}{2W - K}$$

The voltage in circuit B is the current I multiplied by the mutual inductance $= jWM_2 I_1$. Substituting the value of I_1 , the voltage becomes

$$\frac{WM_1 M_2 E_a}{KL_1 L_2} \times \frac{W}{2W - K}$$

25 The current in circuit B is found by dividing this voltage by the impedance of the tuned loop. The impedance of the loop B is by design made the same as that of A. Therefore the current is given by the equation:

$$I_2 = \frac{WM_1 M_2 E_a}{JK^2 L_1 L_2} \times \frac{(W)^2}{(2W - K)^2}$$

The voltage E_1 applied to grid 14 is this current multiplied by the impedance

$$\frac{-j}{WC_1}$$

of the condenser C_1 . Therefore,

$$E_1 = \frac{-M_1 M_2 E_a}{K^2 L_1 L_2^2 C_1} \times \frac{(W)^2}{(2W - K)^2}$$

The voltage E_2 from the image frequency coming through the small condenser 13 will now be determined. The current in condenser 13 will be equal to the voltage E_2 divided by the impedance of the condenser 13 added to the impedance Z_1 of the parallel circuit of coil 5 and condenser 6.

This current

$$I_3 = \frac{E_a}{\frac{-j}{WC_2} + Z_1}$$

now

$$Z_1 = \frac{(jWL_2) \frac{(-j)}{WC_1}}{jWL_2 - \frac{j}{WC_1}} = \frac{\frac{L_2}{C_1}}{jWL_2 - \frac{j}{WC_1}}$$

The denominator of the fraction in the right hand side of this equation is recognizable as the series impedance Z and this has already been reduced to

$$jKL_2 - \frac{(2W - K)}{W}$$

substituting this value,

$$Z_1 = \frac{W}{jKC_1(2W - K)}$$

Substituting this value of Z_1 in the expression for the voltage on grid 14, we find

$$E_2 = \frac{E_a W^2 C_2}{KC_1(2W - K) + W^2 C_2}$$

To make E_1 balance out E_2 the transformer coils will be arranged to make E_1 opposed in phase to E_2 . This may be done by making M_1 and M_2 of

opposite sign. To find the value of C_2 that will make E_1 equal E_2 their sum is made equal to zero, thus,

$$-\frac{M_1 M_2 E_a W^2}{K^2 L_1 L_2^2 C_1 (2W - K)^2} - \frac{W^2 C_2 E_a}{KC_1 (2W - K) + W^2 C_2} = 0 \quad 5$$

When this equation is solved for C_2 ,

$$C_2 = \frac{M_1 M_2 W^2 K C_1 (2W - K)}{W^2 K^2 L_1 L_2^2 C_1 (2W - K)^2 - M_1 M_2 W^4} \quad 10$$

Since $M_1 M_2$ would be in the order of 10^{-9} the right hand expression $M_1 M_2 W^4$ would be negligible compared to the remainder of the denominator. Therefore the equation becomes,

$$C_2 = \frac{M_1 M_2 W^2 K C_1 (2W - K)}{W^2 K^2 L_1 L_2^2 C_1 (2W - K)^2} = \frac{M_1 M_2}{K L_1 L_2^2 (2W - K)} \quad 15$$

With the usual constants for a set of the kind described for use in the broadcast range the condenser C_2 will be in the order of 10^{-13} or .10 micro-microfarad and a condenser of this extremely small capacity will substantially balance out the image signal throughout the broadcast range.

In solving the value of the condenser, any inherent capacity coupling between the circuits A and B was not considered. Such capacity couplings can be made negligible. However, we have found by test that with a slight capacity coupling between the tuned circuits A and B, the required capacity C_2 can be made substantially constant for any frequency in the broadcast band. In practice, it is also preferable to empirically determine the best value of the condenser in the neighborhood of the calculated value.

Since the circuits A and B are tuned to the desired signal and the amount of energy transferred by these circuits when tuned to resonance is in the neighborhood of 40,000 to 50,000 times as great as that transferred at the frequency at which the balance is to take place, the diminution of the desired signal by any energy flowing thru condenser 13 cannot be noticed.

The image frequency may be balanced out by an electromagnetic coupling instead of by the electrostatic coupling. Such an arrangement is shown in Fig. 2.

The image voltage E_1 passing through the circuits A and B and developed across the condenser 6 in this figure is the same as previously given and is as follows:

$$E_1 = \frac{-M_1 M_2 E_a W^2}{K^2 L_1 L_2^2 C_1 (2W - K)^2}$$

By developing the equations along the lines previously given it will be found that the image voltage E_2 passing through the coupling M_x and developed across the condenser 6 is as follows:

$$E_2 = \frac{-E_a M_x}{K L_1 L_2 C_1 (2W - K)} \quad 60$$

By equating E_1 to E_2 it will be found that the desired coupling M_x is as follows:

$$M_x = \frac{M_1 M_2 W^2}{K L_2 (2W - K)} \quad 65$$

By giving this value to the coupling M_x in Fig. 2 and by properly poling the connections of the transformer coil the image frequency will balance out.

The complete circuit is not given in Fig. 2 as it will be understood that the terminals of the condenser 6 may be connected either to any radio frequency tube or to the detector as desired.

It will be understood that we may use any number of tuned loops A and B and we also may

substitute tuned vacuum tube stages for such tuned loops without departing from the spirit of the invention.

While a particular embodiment of the invention has been illustrated in the drawing and described in the specification, the invention is not to be limited thereto as various modifications may be made without departing from the invention set forth in the claims.

Having described our invention, what we claim is:

1. In superheterodyne receiving sets, a source of signal frequency, an oscillator adapted to beat with the signal frequency derived from said source, an inductance-capacity loop tuned to the signal frequency, a detector having means to connect it across points in said loop, there being a magnetic coupling between said source and said loop and a capacitatively reactive circuit coupled between the signal source and said loop having a capacitative reactance value that produces across said points a voltage of the image of said signal frequency equal in value and opposite in phase to the image voltage produced thereacross through said magnetic coupling to prevent the beating action between the oscillator and image frequencies from affecting the detector.

2. In superheterodyne receiving sets, a source of signal frequency, a radio frequency amplifier stage having a circuit tuned to the signal, a detector, a signal selective circuit containing a coil and condenser coupling the signal source and the amplifier, a source of oscillations to beat with the signal and a capacitatively reactive circuit coupled between the signal source and the tuned circuit of the amplifier stage having a capacitative reactance value that produces in the tuned circuit of the amplifier stage a voltage of the image of said signal frequency, equal in value and opposite in phase to the image voltage produced thereacross through said coil, to prevent the beating action between the oscillator and image frequencies from affecting the detector.

3. In superheterodyne receiving sets, a signal source, an oscillator adapted to beat with the signal and image frequencies derived from said source, a circuit tuned to the signal frequency and coupled to said signal source, a second circuit tuned to the signal frequency and coupled to the first mentioned circuit whereby the signal-to-image ratio is increased in the second circuit, a detector connected to the last mentioned circuit, a third untuned circuit coupled between the signal source and said second circuit, the capacities, inductances and coupling of said circuits being of such value as to cause image voltages of substantially equal value and opposite phase at the junction point of said second and third circuits.

4. In a superheterodyne receiving set having a vacuum tube for receiving input energy, a collector circuit of signal and image frequency energy, a circuit tuned to the signal frequency and coupled to said collector circuit, a second circuit tuned

to the signal frequency and coupled to the first-mentioned tuned circuit, whereby the signal-to-image ratio is increased in the second circuit, said second circuit being connected to the vacuum tube, a third untuned circuit coupled between the signal source and the said second circuit, the capacities, inductances and coupling of said circuits being of such value as to cause image voltages of substantially equal value and opposite phase at the junction point of said second and third circuits.

5. The method of selectively transferring signal currents of one frequency without change in frequency, in the presence of undesired signal currents of a slightly different frequency, which comprises transferring two currents of each of said frequencies, proportioning the undesired currents as thus transferred to be equal and opposite, and building up by resonance only one of the signal currents to prevent equality and opposition between the two signal currents as thus transferred.

6. An electrical coupling system having two pairs of terminals, one pair being coupled to the other pair by a tunable selective transfer means and separately by a non-selective transfer means, the non-selective means having, at any frequency within given limits, a transfer ratio equal and opposite to that of the selective means, the selective means being tuned below said frequency by a predetermined constant frequency difference.

7. In a superheterodyne receiver, the arrangement for coupling an antenna circuit to a vacuum tube having an input circuit, and reducing image interference, which comprises tunable selective transfer means for coupling said circuits, and non-selective transfer means for separately coupling said circuits, the non-selective means having, at any frequency within given limits, a transfer ratio equal and opposite to that of the selective means, the selective means being tuned to one side of said frequency by a predetermined constant frequency difference substantially equal to twice the intermediate frequency of said receiver.

8. In a system of the character described, a coupling circuit comprising a tunable and untuned channel in parallel with each other and having their constants so related as to deliver similar impulses at the output thereof in opposed phase relationship, said tunable channel comprising two tuned circuits in cascade and said untuned channel comprising a capacitative connection from the input of said first tuned circuit to said second tuned circuit, said untuned channel having a transmission characteristic such that it transmits frequencies within the operating range of the tunable channel at a substantially low efficiency of the order of the transmission efficiency of said tunable circuits for non-resonant frequencies.
